(57) **CLAIM**

The ornamental design for a rotatable spray shield device, as shown and described.

DESCRIPTION

FIG. 1 is a front-right perspective view of a rotatable spray shield device showing our new design, wherein the rotatable spray shield device is mounted on a circular spray bottle with a conventional spray trigger, the circular spray bottle and the conventional spray trigger shown in broken lines form no part of the claimed invention;

FIG. 2 is a right-rear perspective view of the design shown in FIG. 1, wherein the rotatable spray shield device is mounted on a circular spray bottle with a conventional spray trigger, the circular spray bottle and the conventional spray trigger shown in broken lines form no part of the claimed invention; FIG. 3 is a top-rear perspective view of the design shown in FIG. 1, the internal bores in the nozzle portion of the rotatable spray shield device, which are shown using broken lines, form no part of the claimed invention;

FIG. 4 is another front-right perspective view of the design shown in FIG. 1, the outermost circular element shown in broken lines in the central portion of the device forms a boundary for the claimed subject matter;

FIG. 5 is a left-side elevational view of the design shown in FIG. 1;

FIG. 6 is a right-side elevational view of the design shown in FIG. 1;

FIG. 7 is a front view of the design shown in FIG. 1, the outermost circular element shown in broken lines in the central portion of the device forms a boundary for the claimed subject matter;

FIG. 8 is a rear view of the design shown in FIG. 1, the internal bores in the nozzle portion of the rotatable spray shield device, which are shown using broken lines, form no part of the claimed invention;

FIG. 9 is a bottom plan view of the design shown in FIG. 1; and,

FIG. 10 is a top plan view of the design shown in FIG. 1. The broken line portions of the drawing figures are included to show unclaimed subject matter only and form no part of the claimed design.

1 Claim, 6 Drawing Sheets
